UNITED STATES PATENT OFFICE.

MARTIN IMES, OF LEAVENWORTH, KANSAS.

RAILROAD-TIE.

1,133,727.

Specification of Letters Patent. Patented Mar. 30, 1915.

Application filed January 12, 1914. Serial No. 811,738.

To all whom it may concern:

Be it known that I, MARTIN IMES, a citizen of the United States, residing at Leavenworth, in the county of Leavenworth and 5 State of Kansas, have invented certain new and useful Improvements in Railroad-Ties; and I do hereby declare the following to be a full, clear, and exact description of the invention, such as will enable others skilled 10 in the art to which it appertains to make and use the same.

This invention relates to new and useful improvements in railroad ties and has for its object the provision of a novel means for 15 securing railroad rails to metallic ties.

Another object of my invention is the provision of a metallic tie which will be particularly strengthened throughout its entire life and thereby prevented from breakage 20 owing to heavy traffic.

Another object of my invention is the provision of a tie which will eliminate the spreading of railroad rails and thus prevent accident caused by said spreading.

25 A further object of my invention is the provision of a tie which will eliminate the necessity of using the old wooden tie and yet combine the advantages of the wooden tie with that of the metallic tie.

30 With the above and other objects in view I will now proceed to describe my invention in the following specification and accompanying drawings, in which—

Figure 1 is a top plan view of my improved railroad tie showing the same as it would appear with the rails in place, Fig. 2 is a side view end elevation of my improved railroad tie showing one end thereof partly in section, and Fig. 3 is a transverse sectional view of my improved railroad tie taken on line 3—3 of Fig. 2.

Referring to the drawings by characters of reference 1 indicates generally my improved railroad tie which preferably comprises the centrally located upstanding rib 2 which terminates at its lower extremity in the lateral extensions 3 and 4 respectively. This tie preferably is composed of a single sheet of material and the central rib 2 is stamped therefrom as will be clearly seen upon referring to Fig. 3 of the drawings.

Suitable U-shaped members 5 are provided with the laterally extending flanges 6 which are provided with apertures through which the rivets 7 are adapted to pass by

means of which the U-shaped members are held in place on the tie.

The bight portions 8 of the U-shaped members are preferably so placed that they extend in a plane parallel with the flanges 4 formed on the tie. Thus it will be seen that a seat for the rail will be provided which will prevent the same from overturning.

Suitable wooden blocks 9 are provided and are adapted to form plugs which fill the 65 chambers formed between the arms of the U-shaped members and the central rib of the tie as will be clearly seen upon referring to Fig. 3.

Suitable apertures 10 are provided in the 70 bight portion of the U-shaped members which are adapted to receive the shanks of the spikes when the same are in place.

It will be obvious from the foregoing that owing to the construction of my improved 75 tie the advantages of the ordinary wooden tie are combined with the advantages of a metallic tie and it will be apparent that a tie will be best formed which is substantially imperishable and the only portions thereof 80 which are apt to give out are the wooden blocks and the cost of renewing the same is very slight compared with the expense and material in the replacing of the old type of wooden tie.

It will be apparent that in using the device the blocks are inserted as previously described and the shanks of the spikes driven through the apertures in the U-shaped members, thus entering into the wooden blocks 90 and binding the rail firmly in place in the manner of the ordinary type of railroad tie.

While in the foregoing I have shown and described the preferred embodiment of my invention I wish it to be understood that I 95 may make such changes in combination and arrangement of parts as may fall within the scope of the claim without departing from the spirit of my invention.

What is claimed is:—

A rail tie comprising a longitudinal rib, 100 formed of a single strip of sheet metal bent back upon itself, flanges formed at the lower edge of the rib, said flanges being continuations of the strip of metal, U-shaped rail 105 securing members the bight portions of which form rail seats and overlie the upper edge of the rib, flanges at the ends of the arms of the U-shaped rail securing members said flanges lying on the upper faces of the 110

flanges on the rib, rivets securing the flanges on both the rib and U-shaped members together, and the bight portions of the U-shaped members being formed with spike receiving apertures and wood blocks arranged to be inserted between the arms of the U-shaped members and the rib said blocks being arranged to provide a means

for retaining rail securing spikes in place in the tie. 10

In testimony whereof I affix my signature in presence of two witnesses.

MARTIN IMES.
